UNITED STATES PATENT OFFICE.

EDWARD T. HULL, OF NEW YORK, N. Y.

SPEED-CONTROLLING APPARATUS FOR INTERNAL-COMBUSTION ENGINES.

Application filed July 25, 1922. Serial No. 577,462.

This invention is an improved speed controlling means for internal combustion engines, certain features thereof being particularly applicable to engines serving as the 5 motive power for vehicles.

My improved mechanism provides for both automatic and manual control of the throttle, the throttle being automatically opened and closed in accordance with variations in the load to maintain a substantially definite speed which may be set or varied at will by the manual control. I use the word "manual" throughout this case in its broad meaning to indicate not merely operation by hand, but also by foot or otherwise within the direct will of the operator; and by force applied by him.

One of the main objects of my invention is to provide simple, easily operated, and 20 efficient means whereby the maintenance of the substantially constant desired speed may be temporarily interrupted and the speed reduced to minimum or idling speed by movement of the clutch pedal, and said 25 desired speed is reestablished automatically upon the return of the clutch pedal to normal position. Thus the desired speed determined upon by the driver will be automatically maintained, but in case a temporary 30 slowing down is necessary, as for grade crossings, pressure on the clutch pedal will cause the engine to slow down, and removal of pressure on the clutch pedal will re-establish the automatic governing and bring 35 the engine back to its previous speed.

The driver may maintain his foot in operative relationship to the brake and clutch 40 pedal without the necessity of shifting one foot back and forth for operation of the brake and accelerator alternately in congested traffic conditions. Although the engine speed control may be operated by the clutch pedal, only on a full movement of the latter for disengaging the clutch, preferably 45 the control is operated by only a slight or limited movement of the pedal so that by a slight pressure of the foot the engine and car are slowed down, and by a further movement the clutch is disengaged 50 to permit the car to stop and the engine to idle. The re-engagement of the clutch and then removal of all pressure on the pedal permits the car to at once pick up speed to the previously established limit. The mechanism 55 whereby the aforementioned results are accomplished does not interfere with a

temporary speeding up beyond said limit by pressing the foot accelerator or operating the steering wheel throttle lever, and such speeding up does not disturb the set of the 60 automatic governor or the return to the desired fixed speed when the foot or hand operated accelerator is returned to normal position.

A further object of my invention is to 65 provide means whereby the control of the speed by the operation of the clutch pedal tends to reduce rather than increase the normal resistance to clutch disengagement movement of the pedal.

A further object is to provide means for 70 positively opening or closing the throttle by the manual control, and for operating it from the automatic governor through yielding connections whereby the rapid operation by the manual means does not apply excessive strain to the delicate parts of the governor.

A further object of my invention is to so 75 design the parts that the mechanism may be used in connection with the standard throttle controlling mechanism of a car, without necessitating extensive alterations in the latter.

Other objects and advantages will be 80 pointed out hereinafter, or will be apparent from a consideration of a preferred form shown in the accompanying drawings. In 85 these drawings:

Fig. 1 is a top plan view showing somewhat diagrammatically a portion of a motor vehicle equipped with a preferred form of my improved device.

Fig. 2 is a side elevation, and

Figs. 3 and 4 are sections on the lines 90 3-3 and 4-4 respectively of Fig. 1, and on a larger scale.

I have illustrated my invention as applied 95 to a motor vehicle having a motor of the V-type with an upwardly extending intake 100 conduit 10 delivering through branch conduits 11 to a pair of intake manifolds 12. The intake conduit 10 is provided with a throttle 13 mounted on a rock shaft or spindle 14 which may be oscillated to open 105 and close the throttle.

The standard parts for the manual control of the throttle include a hand operated lever 15 mounted on the steering wheel and a foot operated lever 16 in the usual position. The hand lever is mounted on a rod 17 which projects through the steering col-

umn and is provided with a gear 18 meshing with a segment 19, which latter is connected by a link 20 to one arm of a bell crank lever 21. The foot lever ordinarily known as the 5 accelerator, is mounted on a pivot 22, and has an arm connected by a link 23 to another arm of the bell crank lever 21. A third arm of the bell crank lever 21 is connected by a link 24 to a lever arm 25 on 10 the throttle spindle 14. Thus, by pressing on the accelerator 16, or operating the hand lever 15 in the proper direction, a pull is exerted on the rod 24 and the spindle 14 is turned in a counter-clockwise direction as 15 viewed in Figs. 2 and 4, and the throttle is opened to the desired extent.

In the various figures the arrows associated with the moving parts indicate the direction of movement of those parts in an 20 opening of the throttle. Obviously they move in the reverse direction for closing. The parts so far described are not new with me, and may be of any suitable type or character adapted to accomplish the desired 25 result of manually controlling the throttle by the use of the hand or foot. The rod 20 has the usual lost motion connection with the bell crank lever 21 to permit operation of the throttle without movement of the 30 hand lever 15, and the bell crank lever has lost motion connections with the rod 24 to permit operation of the throttle by the automatic governor hereinafter referred to, and without operation of the bell crank lever.

35 For automatically controlling the throttle to maintain any desired fixed speed, I employ a suitable governor driven by and operating in accordance with the speed of the engine. I do not wish to be restricted to 40 any particular type of governor, as any means which will exert an operating force in accordance with the speed of the engine may be employed.

The device illustrated is of the ball govern- 45 nor type, and is mounted in a casing 26 carried by suitable supports 27 attached to the body of the engine. I have not illustrated any of the details of this governor, as they form no portion of my present in- 50 vention, but the parts may be substantially identical with those illustrated in my co-pending application, Serial No. 538,813, filed February 23rd, 1922. The main shaft of the governor has a pinion 28 meshing with 55 a gear 29 on a shaft 30. The latter may be any suitable shaft forming a part of the engine, as for instance that employed in driving the fan 31 or other parts such as the magneto, generator, water pump, or the like. 60 The governor illustrated has a non-rotatable longitudinally movable rod 32 which moves toward the right from the position illustrated in Fig. 2 upon increasing the speed of the engine. This rod has pivotal connec- 65 tions to a lever 33 intermediate of the ends

of the latter, and one end of this lever is connected to the throttle spindle 14 by the mechanism shown particularly in Fig. 4. An arm 34 is secured intermediate of its ends to the throttle spindle 14, and one end is connected by a tension spring 35 with the upper end of the lever 33. The opposite end of the arm 34 is connected by a pair of pivotally connected links 36 and 37 to the upper end of the lever 33. The link 36 normally lies approximately parallel to the arm 34, while the link 37 normally lies substantially parallel to the spring 35 and substantially at right angles to the lever 33. The upper ends of the arm 34 and link 36 are adjacent to each other, and the parts are so designed that they cannot pass each other, but they can be separated by an extension or stretching of the spring 35. Thus, if the lower end of the lever 33 be fixed, an increase in speed of the engine will move the rod 32 endwise and swing the upper end of the lever 33 toward the right (see Figs. 2 and 4) and will thus move the throttle toward closed position. For this operation the spring 35 will keep the upper ends of the link 36 and arm 34 together. Obviously a slowing down of the engine will move the rod toward the left and will swing the arm 34 counterclockwise about the throttle spindle to open the throttle and permit the engine to pick up to the fixed or desired speed.

For setting the governor or establishing the speed at which it is desired to maintain the engine, I provide means for varying the position of the lower end or fulcrum of the lever 33. As shown, this means includes a bell crank lever 38 having an arm 39 connected by a link 40 to the lower end of the lever 33. Another arm 41 of the bell crank lever is connected by a rod 42 to an arm 43 on a rock shaft 44 substantially parallel to the steering column and mounted in brackets 44^a carried by the latter. The upper end of the rock shaft 44 is provided with an operating handle or lever 45 movable over a segment 46 whereby the lever may be locked in any desired position. By the oscillation of this lever and the rock shaft the lower end of the lever 33 which normally serves as a fulcrum may be adjusted at will. A movement of the fulcrum of the lever 33 toward the right will open the throttle, and the resulting increased speed of the engine will thereafter be maintained by the action of the governor. It will be noted that a rotation of the throttle spindle by the movement of the lever 33 also moves the arm 25 and rod 24, but due to the lost motion connections between the rod 24 and the bell crank lever 21, the latter is not moved, and thus the load on the governor is reduced to a minimum.

To slow down the engine to idling speed

by operation of the clutch pedal, the bell crank lever 38 is provided with an arm 47 connected by a rod 48 to the clutch operating mechanism. The clutch pedal 49 is mounted on a pivot 50 and is connected by a link 51 to an arm 52 on the clutch operating rock shaft 53, so that by pressure on the clutch pedal the rock shaft is caused to turn in a clockwise direction. I have not illustrated the clutch nor the usual heavy spring for normally holding the clutch parts engaged, but it will be understood that the clutch may be of the usual type and operated in the usual manner from the rock shaft 53. Merely as a diagrammatic representation of the heavy clutch spring, I have shown a spring 54 operating as the equivalent of, or a diagrammatic representation of the main clutch spring. The rod 48 is pivotally connected to an arm 55 secured to the clutch operating rock shaft 53 so that when the clutch is disengaged by pressure on the clutch pedal, the rod 48 will be positively pushed to swing the bell crank lever 38 and move the fulcrum of the lever 33 toward the left. A suitable spring 56 is employed for slightly assisting in this operation and acting against the main clutch spring 54. The force of the spring 56 is more than sufficient to overcome the spring 57, and if necessary the spring 35, and the inertia of the parts operated by the rod 48. Therefore, the closing of the throttle by pressure on the clutch pedal does not make the pedal any harder to operate than without my improved mechanism, and in fact the spring 56 aids slightly in the operation of the pedal.

The arm 39 of the bell crank lever 38 is also provided with a spring 57 which normally tends to move the fulcrum of the lever 33 toward the right and take up lost motion in the parts. The lengths of the arm 55 in respect to the bell crank lever arm 47 is preferably such that a comparatively slight movement of the clutch pedal 49 will operate to close the throttle, and before the clutch pedal has been moved far enough to actually disengage the clutch. Thus the driver, by applying a slight pressure on the clutch pedal, slows down the engine to the desired extent. Thus the car may be slowed down for a grade crossing or other traffic condition without disengaging the clutch. And a further slowing down or stopping may be accomplished by further pressure on the clutch pedal so as to actually disengage the clutch.

It will be noted that by reason of the operative connections between the throttle and the actuating mechanism the operation of one is not in any way prevented by any particular adjustment of another. For instance, if the clutch be disengaged when the governor controlling lever 45 is set for

higher speed, the arm 41 of the bell crank lever may slide down on the rod 42 without moving the latter.

If the driver desires to race the engine when the governor controlling lever 45 is set for low speed, the throttle may be positively opened by either the hand lever 15 or the foot lever 16 working through the rod 24 and the throttle spindle arm 25. This will extend the spring 35 without moving the lever 33, or putting undue strain on the governor. If the governor controlling lever 45 be suddenly moved from one extreme position to the other, the throttle will instantly follow by a swinging of the lever 33 about the end of the rod 32 as a fulcrum, and the lost motion connection between the rod 24 and the bell crank lever 21 will permit movement of the rod without swinging the lever.

If the driver desires to race the engine while the clutch is disengaged, this will be permitted by reason of the spring 35 which will let the throttle spindle be turned by rod 24.

In the mechanism illustrated the speed of the engine is controlled by an opening and closing of the throttle. This throttle constitutes merely one form of fuel controller which may be employed, as other type of engines may have the speed varied by controlling the supply of fuel or other motive fluid by means of other forms of controllers.

Having thus described my invention, what I claim as new and desire to secure by Letters Patent is:

1. Means for controlling the speed of the internal combustion engine of a motor vehicle, including a fuel supply controller, means for moving said controller to idling speed position upon disengaging the clutch between the engine and the mechanism driven thereby, and manually actuated operating mechanism for said controller independent of said means whereby the speed of the engine may be varied at will while the clutch is disengaged.

2. Means for controlling the speed of the internal combustion engine of a motor vehicle, including a fuel supply controller, an automatic governor operatively connected thereto for maintaining the speed of the engine substantially constant under varying conditions of load, means for moving said controller to idling speed position upon disengaging the clutch between the engine and the mechanism driven thereby, and independent manually actuated operating mechanism for said controller whereby the speed of the engine may be varied at will while the clutch is disengaged.

3. The combination with the fuel supply controller of a motor vehicle engine, of a lever for operating the same, an automatic governor driven by the engine and connected

to said lever for maintaining the speed of the engine substantially constant under varying load conditions, means for varying the position of the fulcrum of the lever to change the speed at which the engine is to be maintained, means for varying the position of the fulcrum of the lever to close the fuel controller upon disengaging the clutch between the engine and the mechanism driven thereby, and manually actuated means independent of said lever for operating the fuel controller to vary the speed of the engine at will.

4. A motor vehicle having in combination with the engine throttle, clutch pedal and clutch spring, an automatic speed governor having operative connections with the throttle to maintain the speed of the engine substantially constant, and means actuated by the clutch pedal for varying the operative relationship between the governor and throttle to reduce the speed of the engine when the clutch is disengaged, said means includ-

ing a spring acting in opposition to the clutch spring.

5. The combination with the throttle valve of a motor vehicle engine of a pair of separate levers connected thereto, an automatic governor driven by said engine, a lever connected intermediate of its ends to said governor, yielding connections between one end of said last mentioned lever and one of said first mentioned levers, manually operable means positively connected to the other of said first mentioned levers for operating said throttle, manually operable means for adjusting the normal position of the other end of said third mentioned lever, and means for moving said last mentioned end of said last mentioned lever to close the throttle upon disengaging the clutch between the engine and the mechanism driven thereby.

Signed at New York in the county of New York and State of New York this 24th day of July A. D. 1922.

EDWARD T. HULL.
